UNITED STATES PATENT OFFICE.

HERMANN WEDER, SR., AND CHARLES H. WOLFF, OF PHILADELPHIA, PENNSYLVANIA.

DESIGN FOR A SPECULUM.

44,389.

Specification for Design.

Patented July 22, 1913.

Application filed April 24, 1913. Serial No. 763,454. Term of patent 7 years.

To all whom it may concern:

Be it known that we, HERMANN WEDER, Sr., and CHARLES H. WOLFF, citizens of the United States, residing at Philadelphia, in the county of Philadelphia and State of Pennsylvania, have invented a new, original, and ornamental Design for a Speculum, of which the following is a specification, reference being had to the accompanying drawing, forming a part thereof.

The figure is a perspective view of a speculum in which the blades are connected

together by a loop the rear of which has the appearance of two superimposed spaced apart annular bands.

We claim:

The ornamental design for a speculum, as shown and described.

HERMANN WEDER, SR.
CHARLES H. WOLFF.
